UNITED STATES PATENT OFFICE.

ROBERT KAUCH AND CHARLES L. PAULUS, OF DAYTON, OHIO.

SPADE GRIP.

Application filed July 17, 1924. Serial No. 726,552.

To all whom it may concern:

Be it known that we, ROBERT KAUCH and CHARLES L. PAULUS, citizens of the United States, residing at Dayton, in the county of 5 Montgomery and State of Ohio, have invented certain new and useful Improvements in Spade Grips, of which the following is a specification.

This invention relates to spade grips or 10 the like and has particular reference to such employing a trigger operable by the forefinger of the hand gripping the spade grip.

It is of importance in the art to provide whatever means are possible not only for the 15 absorption of shock and means for steadyng the firing action of the operative but also to provide means for the eventuality that either the right hand or the left hand may be required for trigger operation. It is 20 with a view to disclosing mechanism for obtaining the above improvements that the attached drawings are incorporated with the present specification, in which—

Fig. 1 constitutes a vertical sectional view 25 of one embodiment of the device;

Fig. 2 is an end view of the same;

Fig. 3 comprises a side view opposite to that shown in Fig. 1; and

Fig. 4 is a plan view from below but not 30 showing the chin rest.

Clearly the first important feature required for steadyng the operative's arm is the absorption of shock. To this end the frame of the spade comprises a mounting 35 for gun bolt absorbing device in which a plunger 2 is resiliently backed by a series of fiber buffer discs 3 which are maintained in position by a screw 4, or the like, locked in assembly by means of a locking pin 5 40 biased by a suitable spring 6. A handle of hardwood, or the like, 7 is mounted on the frame by means of a sleeve 8 which latter conveniently carries a trigger operating plunger 9 in a central manner to be operated 45 whether right handedly or left handedly as will be explained below. The gun trigger 10, forming a part of the gun proper (not shown) is in reality actuated by means of an auxiliary trigger device 11 biased to a normal 50 inoperative position by virtue of a flat spring or the like, 12.

It will be observed (see Fig. 2) that the operating lever 13 provided for actuating the pin 9 is fulcrumed righthandedly by 55 means of pin 14 fitting into a lefthand hole

114, or for left handed action the lever 13 is to be optionally reversed with the pin 14 now engaging a hole 16. The plunger 9 being arranged practically central of the two positions enables the change over to be made 60 with the least number of parts concerned.

It is the auxiliary trigger 11 that is rotated by depression of the plunger 9, which action causes operation of the gun trigger 10 by contacting therewith. However, in 65 order more readily to mount and dismount the spare handle from the gun itself a fulcrum pin 15 is provided for the auxiliary trigger 11, which pin is excentrically attached to support 115 rotatably mounted on 70 the frame. The means for changing the relative position of the fulcrum pin will be described later.

In conjunction with said trigger operating device there is also made use of chin 75 support or rest 17 made up of a sponge rubber pad, or the like, 18, within a sheet metal receiver 19. It is the receiver that is demountably attached to the frame 1 by virtue of a threaded hole 20. Thus the operative 80 can most easily and steadily sight along the barrel of the gun without fear of shock or disturbance.

It may be said that in devices above referred to it is very advisable to provide a 85 "safety" and "armed" position for the trigger control mechanism. Thus the adjustable eccentric device, 115, is preferably made integral with a lever 21 carrying a movable locking bolt 22 for engagement 90 whether with an "armed" hole 222 or a "safety" positioning hole 23. Finally, attention is to be drawn to the further steadyng features 24 comprising a projection for preventing the shifting of the operative's 95 hand during action.

In operation therefore the positioning bolt 22 is first adjusted to the desired setting. If firing is to be done the operating lever 13 is depressed for indirect engagement with the gun trigger 10. The operation of sighting will be least disturbed by virtue first of the chin rest 16, secondly the hand positioning projection 24 and thirdly the bolt shock absorbing feature 2, 3. 105

We claim:

1. In combination with a handle, a centrally positioned trigger operating element, and a finger operated means for operating said element, demountably supported with re- 110

spect to said element for right hand or left hand operation.

5 2. In combination with a handle, a centrally positioned trigger operating element passing through said handle, and a finger operated means for operating said element, demountably supported with respect to said element for right hand or left hand operation.

10 3. In combination with a cushioned handle for gun bolt shock, a centrally positioned trigger operating element, and a finger operated means for operating said element, demountably supported with respect to said element for right hand or left hand operation.

15 4. In combination with a cushioned handle for gun bolt shock, a centrally positioned trigger operating element passing through said handle, and a finger operated means for operating said element, demountably supported with respect to said element for right hand or left hand operation.

20 5. In combination with a cushioned handle for gun bolt shock, a shock relieving chin rest for said handle, a centrally positioned trigger operating element passing through said handle, and a finger operated means for operating said element, demountably supported with respect to said element for right hand or left hand operation.

25 6. In combination with a cushioned handle for gun bolt shock, a shock relieving chin

30 rest for said handle, a centrally positioned trigger operating element passing through said handle, a finger operated means for operating said element, demountably supported with respect to said element for right hand or left hand operation, and a hand positioning means on said handle.

35 7. In combination with a demountable spade handle, a trigger actuating element mounted on said handle for contacting with the trigger of a gun, said element eccentrically mounted, and means for operating said eccentrically mounted element for avoiding contact with the trigger of the gun.

40 8. In combination with a demountable spade handle, a trigger actuating element mounted on said handle for contacting with the trigger of a gun, said element eccentrically mounted, and locking means for operating said eccentrically mounted element for avoiding contact with the trigger of the gun.

45 9. In combination with a spade handle, an auxiliary trigger lever for contacting with the trigger of a gun, a rotatable eccentric mounting for said lever, a control lever for said eccentric mounting, and a locking pin for said control lever to lock said eccentric mounting to bring said auxiliary trigger into contacting or non-contacting position.

50 In testimony whereof we affix our signatures.

ROBERT KAUCH.

CHARLES L. PAULUS.
